UNITED STATES PATENT OFFICE

159,928

GAME BOARD

Harry Alfred Reising, La Grange, Ill.

Application August 14, 1948, Serial No. 148,115

Term of patent 3½ years

(Cl. D34—5)

To all whom it may concern:

Be it known that I, Harry Alfred Reising, a citizen of the United States, residing at La Grange, county of Cook, and State of Illinois, have invented a new, original, and ornamental Design for a Game Board, of which the following is a specification, reference being had to the accompanying drawing, forming a part thereof, in which:

I claim:

The ornamental design for a game board, as shown.

HARRY ALFRED REISING.
